UNITED STATES PATENT OFFICE.

CLARENCE L. MULDER, OF MILWAUKEE, WISCONSIN.

AUTOMOBILE SIGNAL.

Application filed July 22, 1922. Serial No. 576,723.

To all whom it may concern:

Be it known that I, CLARENCE L. MULDER, a citizen of the United States, and resident of Milwaukee, in the county of Milwaukee, 5 and State of Wisconsin, have invented certain new and useful Improvements in Automobile Signals; and I do hereby declare that the following is a full, clear, and exact description thereof.

10 The invention relates to a signal affixed to the rear of an automobile operative to indicate the slowing up or stopping of the car.

It comprises a stop sign plate pivotally supported in a suitable place in the rear of the automobile, and a wire running therefrom to a brake pedal, whereby on the depression of the brake, the sign is lifted into position to reveal the word "Stop."

20 It is the object of the invention to provide a structure of especial simplicity, easy to manufacture, cheap, made up of a minimum number of parts, and durable. In the daytime, it is operative without the use of electric current, and at night, its use results in no additional expenditure of current as it is adapted to be illuminated by the ordinary tail-light. Its visibility is increased by the reflection of the light thrown by cars following the machine on which the device is installed. A chief operative part is a strong piece of wire, so that there is nothing to wear or get out of order. It may be installed by anyone in a few minutes, not necessitating the attention of an electrician or skilled hand.

With the above and other objects in view which will appear as the description proceeds, the invention resides in the novel construction, combination and arrangement of parts substantially as hereinafter described and more particularly defined by the appended claim, it being understood that such changes in the precise embodiment of the 40 herein disclosed invention may be made as come within the scope of the claim.

In the accompanying drawing, is illustrated one complete example of the physical embodiment of the present invention constructed according to the best mode so far devised for the practical application of the principles thereof.

Figure 1 shows, in side elevation, the device applied to a fender and brings out its 55 operativeness diagrammatically.

Figure 2 is a rear elevation of the sign plate in operative position.

Figure 3 is a section on the line 3—3 of Figure 2.

Figure 4 is a section on the line 4—4 of 60 Figure 2, and

Figure 5 is a rear view showing the invention applied in a different place from that illustrated in Figure 1.

Support 10 is made of thin metal and is 65 bent angularly to form a securing portion 11, which, by screw 12, is adapted to be affixed to a fender 13. The support has a flat upper surface, from which two fingers 14—14' extend rearwardly, the metal immediately adjacent the fingers 14—14' being formed into narrow bands and bent upwardly, forming bearings 15—15' for pivot rod 16. Sign plate 17 is substantially rectangular. At its lower edge it is bent to form 75 grips enveloping pivot rod 16. Between the grips, the metal is bent rearwardly at 18, then downwardly at 19, providing a strip 20 adapted to contact with support 10 and limit the pivotal movement of sign plate 17. 80 A helical spring 21 is coiled on rod 16, one end contacting with the upper surface of support 10, and the other in engagement with the sign plate, tending to move the plate to the position shown in Figure 1. 85 The sign plate has the word "Stop" suitably inscribed thereon, the color of the background being made such as to accentuate the visibility of the word. Rod 16 extends upwardly on one side of the plate, and is 90 gripped by a finger 22 outwardly extending therefrom. It is deflected downwardly and passed into an eye 24 which grips that portion of the rod which is immediately below the finger 22. A wire 25 is secured at one 95 end to eye 23, and at the other to a spring 26, from which a wire 27 leads to a retainer 28, from which wire 29 extends to a band 30, gripping the brake lever 31 immediately beneath the pedal 32. From retainer 28, wire 33 is directed thru an eyelet 34 on the cowl 35, whence it extends upwardly thru an eyelet 36 on the dash 37, a ring 38 being secured to its end. Obviously on the depression of brake lever 31, 100 wires 29, 27 and 25 are operative to swing sign plate 17 into the position shown in Figure 2, where it will be visible for signalling purposes. The invention is not limited to the specific application to a brake lever, but 105

110

may be applied to a clutch or operated in any suitable manner. Ring 38 is provided for the convenient manual manipulation of the device. Spring 26 may be dispensed with, if desired, the wire being given sufficient slack to prevent it from restricting the depression of the brake pedal. Support 10 need not necessarily be affixed to the rear fender 13, but may be located in any suitable place. In Figure 5 is illustrated a very desirable location, the light 39 being immediately adjacent and providing light rendering the sign clearly visible.

It is obvious that the device may be readily installed. There is no possibility of its getting out of order and its operation in-

volves no expenditure of electric current; the parts are few and simple so that it is easily manufactured.

I claim:

The combination of a sign plate, a pivot rod therefor, supporting means for said pivot rod, said pivot rod being bent at the end of said sign plate and extended along the side of said plate, and a finger on said sign plate gripping said pivot rod whereby said pivot rod is maintained in position.

In testimony that I claim the foregoing I have hereunto set my hand at Milwaukee, in the county of Milwaukee and State of Wisconsin.

CLARENCE L. MULDER.
